UNITED STATES PATENT OFFICE.

JOSHUA M. SMITH, OF SPRINGFIELD, ASSIGNOR OF ONE-HALF TO CHARLES F. WOLFE, OF NEW MOOREFIELD, OHIO.

SCALPING AND BOLTING MACHINE.

SPECIFICATION forming part of Letters Patent No. 430,789, dated June 24, 1890.

Application filed July 9, 1889. Serial No. 316,971. (No model.)

To all whom it may concern:

Be it known that I, JOSHUA M. SMITH, a citizen of the United States, residing at Springfield, in the county of Clark and State of Ohio, have invented certain new and useful Improvements in Scalping and Bolting Machines, of which the following is a specification, reference being had therein to the accompanying drawings.

10 This invention relates to certain new and useful improvements in scalping and bolting machines; and the object is to produce a more valuable grade of flour by separating from the partially reduced or cracked wheat, at a suitable stage in its partial reduction, such particles or flakes of bran and germ as may be mixed therewith, whereupon the middlings sifted therefrom are rendered purer and the subsequent reduction thereof more rapid and 20 profitable by reason of the absence therefrom of the bran and other impure portions.

In the accompanying drawings, forming a part of this specification, and in which like reference-letters indicate corresponding parts, 25 Figure 1 represents a vertical longitudinal section of the separator on the line $y-y$ of Fig. 5; Fig. 2, a transverse vertical section of a part of the machine on the line xx of Fig. 1; Fig. 3, a side and end elevation of a brush 30 and its mountings; Fig. 4, a side elevation of a portion of one of the link-belt guides and a cross-section of the driving-shaft; Fig. 5, a plan view of the separator with the feed-hopper and the casing removed, portions of the 35 machine being broken away to show the construction; Fig. 6, a plan view of one of the sieves detached; Fig. 7, a transverse section of one of the link-belt guides and a side elevation of one end thereof, with a bracket secured thereto, and a roller and its adjustable bearing; and Fig. 8, a side elevation of the bracket detached, a roller-box, and the means 40 for adjusting it, a portion of the bracket being broken away.

45 The letter A designates the frame of a scalping and bolting machine, with the necessary inclosing-casing. Suspended therein by the hangers B and the cords C (to be more fully described hereinafter) is an inclined

trough or frame D, having a ledge D' at each 50 side thereof for the support of removable frames E, to which are connected sieves E', of various degrees of fineness. These frames are held in place by beads or strips E'', and are removable endwise through the slotted 55 cross-piece, as shown at D''. The particles or flakes of bran and germ are separated from the flour by passing over the sieves, and are discharged as tailings into the hopper F, while the flour passes through the sieves into 60 the hoppers G below.

In the plan view, Fig. 5, are shown two compartments, side by side, formed by dividing the trough longitudinally by a partition D'', and each compartment has two grades 65 of sieves. If desired, I may use but one compartment and one or more grades of sieves therein, or I may use a plurality of compartments with grades of sieves therein, according to circumstances. In this way I may take 70 the grain near its first stage in gradual reduction, pass it through one compartment of my separator, send the resulting products by the usual means to the rolls or other machine, and return them to adjacent compartments 75 in the same separator for further treatment. It is a well-known fact in the art of flour-milling that the more perfectly we can remove all impure or deleterious portions of the grain before the final reduction to flour 80 the better will be the resulting product.

The meshes of the sieves are inclined to become filled in by particles that are too large to pass through readily. I will now describe my device for keeping the meshes open. Rigidly secured to the sides of the said trough D by means of the supports H are link-belt guides I, (preferably of the form shown in section in Figs. 2 and 7,) with a suitable track for the link belt J along each edge, and having secured to the upper and lower ends, respectively, the brackets K and K', which respectively support the shafts L and L', on which are mounted the smooth rollers M, that carry the aforesaid link belts J, to which motion is imparted by means hereinafter described. The said brackets K are slotted, as shown in Figs. 1, 7, and 8, each having a box

s' slidingly mounted therein, adjustable by means of a screw-threaded bolt *q*, one end of which engages with said box and the other end of which slides back and forth in the 5 socket *r*, according to the way the nut *s* is turned, whereby the tension on each of the link belts *J* may be conveniently adjusted. Access is had to these parts by opening the door *N* in the casing. The said link belts *J* 10 carry one or more pairs of brackets *P*, in each one of which is mounted a sliding box *P'*, held in its adjusted position by set-screws *Q* and supporting one end of the shaft of a transverse cylindrical revolving brush *R*, the function of which is to clear the meshes of the 15 clogging particles before mentioned. The degree of the contact of the brush with the sieves may be varied, as by adjusting the boxes *P'*, as before suggested, and when the 20 bristles have become bent by revolving the brush in one direction they may be restored to their normal position by reversing the brush in its bearings, so that it will revolve in a contrary direction. Motion is transmitted to the 25 said link belts *J* by means of sprocket-wheels *S*, (one to each belt,) mounted on a revolving shaft *T*, turning in bearings *T'*, carried by the frame *A*, and extending through an elliptical opening *U* in each of said link-belt 30 guides *I*, which may have a metallic plate *U'* as a re-enforcement at that point, with a corresponding opening for the shaft, as shown in Fig. 4. Why this opening is elliptical will presently appear. Near each end of said shaft *T* is 35 also mounted a quadrilateral inside bearing-cam *V*, the groove, recess, or slot of which guides a roller *W*, turning on a pin or stud *Y*, secured near the lower end of each hanger *B*, before mentioned, which is pivotally connected to the said trough *D* by a stud or pin-bolt *Z*, and likewise near the upper end to the frame *A* by a bolt *a*. If preferred, the said 40 stud *Y* may be used without the roller *W*. As the said cam *V* revolves, it guides the said roller *W* and causes the hanger *B* to oscillate in a small arc about the bolt *a*. This vibrating motion will be transmitted in sudden jars to the said trough *D* and all its rigid connections aforesaid by means of the pivot-bolt *Z*, 45 whereby the action of the sieve on the particles of grain is accelerated. In the drawings, Fig. 1, the cam is shown somewhat enlarged, in order to show clearly its design and intended action. I do not wish to confine myself to 50 a cam of four sides, but may use one of any number of sides on the same principle, according to circumstances. The lower end of said trough *D* is supported by cords *C*, before mentioned, each of which winds on a 55 drum or pulley *b*, mounted on a shaft *c*, turning in bearings *d*, supported by frame *A*. Near each end of said shaft *c* is mounted a ratchet-wheel *e*, engaging with a pawl or check *f*, pivoted to the frame *A* by the bolt *g*. 60 A crank *h* is fitted on each end of the shaft *c* to rotate it, and thus change the inclination 65 of the trough, as desired, which may be done while the machine is running.

The shaft *T* is rotated by means of a pulley *i* on one end, while the sprocket-wheel *j* on 70 the other end transmits its motion through a link belt *k* to a sprocket-wheel *l*, mounted on the corresponding end of the shaft *m*, turning in bearings *n*, supported by the frame *A*, and having a feed-roll *o* mounted on said 75 shaft *m*, whereby a constant stream is fed from the hopper *p* into the upper end of each compartment in the trough *D*. The amount of the supply is regulated by means of a spring-controlled hinged side *p'* at each compartment of the said hopper *p*, having secured near its lower edge a screw-threaded curved bar *p''*, passing through a stop *a'* on the frame *A*, and having a coiled spring *r'* 80 between said stop and said side of hopper *p'*, 85 which tends to close the opening *q'*, through which the feed passes, but is resisted and controlled by the hand-wheel *r'* on the outer end of the said bar *p''*. It will be observed that the rotation of the brushes is effected 90 by their impact with the sieves as the link belts *J* move. This action causes the brushes to project into or through the meshes of the sieves, with the cleaning effect already suggested. 95

It will be understood that the term "middlings" refers to the material which passes through the sieves up to the time that it becomes so fine as to come under the denomination of "flour," after which the material passing through the sieves or bolting-cloth is properly called "flour." It will also be understood that my machine can be used from the time the wheat is passed through the first rolls until after its final reduction. After 105 the wheat has been reduced to a fine state the finer sieves will be used, so that the term "sieves of varying fineness" will include the ordinary bolting-cloth as well as the sieves proper. The bolting-cloth will be used after 110 the material has reached the proper degree of fineness, whether by the action of the rolls or by previous treatment by this machine. The sudden jar given by the cam to the vibrating trough is valuable, because it materially acts in shaking the particles out of the 115 meshes, thus aiding to keep them clear. This sudden action also facilitates the sifting operation.

Having thus fully described my invention, 120 what I claim as new, and desire to secure by Letters Patent, is—

In a scalping and bolting machine, the combination, with a stationary frame, hangers depending therefrom, a screen-frame having 125 screens and suspended by the hangers, supports depending from the screen-frame, belt-guides fastened to said supports, rollers mounted in the guides, endless belts carried by the rollers, rotatable brushes carried by 130 the belts and arranged to be rotated by being drawn on by the belts as they project

into the sieves, a cam having sharp angles in its groove and engaging the sieve-frame, and a sprocket on the cam-shaft operating the said belts, whereby a swinging sieve-frame with sudden jerks in its vibration is combined with a brush penetrating the sieves and rotated by impact therewith.

In testimony whereof I affix my signature in presence of two witnesses.

JOSHUA M. SMITH.
